REFRESHMENT STAND

Filed Feb. 28, 1931

UNITED STATES PATENT OFFICE

WATHEN M. JAMES, OF DENVER, COLORADO

REFRESHMENT STAND

Application filed February 28, 1931. Serial No. 518,028.

This invention relates to a refreshment stand and has for its principal object the provision of a refreshment stand above which will be a constantly rotating top carrying sign boards for the display of advertisements.

Another object of the invention is to so construct the rotating top that it will form a component part of the stand; and so that it will be substantial and rigid to withstand wind and weather conditions; rain proof, and so that it can be easily rotated so as to require but a minimum of power.

A further object of the invention is to so construct the stand that the operating mechanism will be above the used or dispensing portion thereof so that it will not obstruct the operators nor occupy valuable floor space.

Other objects and advantages reside in the detail construction of the invention which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

30 Fig. 1 is a side elevation of a refreshment stand in which the invention is embodied. This view is partially broken away to illustrate the interior construction.

Fig. 2 is an enlarged vertical section through the top of the stand.

Fig. 3 is a similar, horizontal section taken on the line 3—3, Fig. 2.

The stand proper comprises a dispensing portion 10 provided with hinged doors 11, which when lowered form serving counters. Above the dispensing portion 10 is a machine chamber 12 arranged to enclose the operating mechanism.

The machine chamber is covered at its top by means of a rotating cap 13 so that the entire stand presents the appearance of a lighthouse.

A pair of signboards 14 project outwardly from each side of the cap 10 to carry suitable advertising. These signboards are rigidly

mounted on the cap so that they rotate therewith and are formed to simulate light beams projecting from the cap. If desired, they may be outlined by means of neon tubes 15.

The cap 13 is carried on a vertical central shaft 16 which extends through thrust bearings 17 supported in the machine chamber 12. The cap is rigidly supported from the shaft 16 by means of a suitable frame 18. The shaft 16 is rotated by means of a motor 20 acting through any suitable speed reducing mechanism 21 and a flexible coupling 22.

The top of the machine chamber 12 terminates in an annular ceiling ring 19 which extends upwardly within the bottom of the skirt of the cap 13 so as to prevent rain and moisture from entering the structure at this point.

The faces of the signboards 14 are illuminated by means of floodlights 23 carried on brackets 24 from the central shaft 16. These floodlights shine through windows 25 in the cap 15 directly upon the faces of the signboards 14.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A refreshment stand comprising: a dispensing compartment; a machine compartment arranged above said dispensing compartment; a vertical shaft extending upwardly from said machine compartment; a rotatable cap for said machine compartment supported by said shaft; means for rotating said shaft; and an annular ring surrounding the top of said machine compartment and extending within said cap so as to prevent moisture from entering the former.

2. A refreshment stand comprising: a dispensing compartment; a machine compartment arranged above said dispensing compartment; a rotatable cap above said machine compartment; means within said machine compartment for rotating said cap;

and signboards projecting from said cap and adapted to rotate therewith.

3. A refreshment stand comprising: a dispensing compartment; a machine compartment arranged above said dispensing compartment; a rotatable cap above said machine compartment; means within said machine compartment for rotating said cap; signboards projecting from said cap and adapted to rotate therewith; windows in said cap and floodlights adapted to illuminate said signboards, said floodlights being carried within said cap and adapted to project light beams through said windows.

10 15 In testimony whereof, I affix my signature.
WATHEN M. JAMES.
